UNITED STATES PATENT OFFICE.

CHARLES GILBERT HALL, OF HASLEMERE, ENGLAND.

TRANSFER MECHANISM.

1,135,789.

Specification of Letters Patent. Patented Apr. 13, 1915.

Application filed February 16, 1914. Serial No. 819,009.

To all whom it may concern:

Be it known that I, CHARLES GILBERT HALL, military tutor, a subject of the King of Great Britain, residing at Shottermill, 5 Haslemere, in the county of Surrey, England, have invented certain new and useful Improvements in Transfer Mechanism, of which the following is a specification.

This invention relates to improvements in 10 the devices for the transfer or carry-on from one registering drum to the next in cash registers and other machines intended for the mechanical adding of either numerals or monetary units.

15 The devices to be described are only applicable to a machine which requires a special key-lever or one of a series of special key-levers to be depressed every time before the operation of any one of the usual 20 series of adding key-levers. The function of these special keys, except in so far as they assist in the operation of transfer, will not be referred to, as such function is no part of the present application, and as any one of 25 these special keys is sufficient for the transfer, only one of such keys will be shown. The transfer is effected by a spring-pulled compound lever which is withdrawn from contact with a registering drum by means of 30 a universal yoke, the yoke being depressed by any one of the special key-levers. The force necessary to cause transfer is stored up by two detents acting upon the compound lever, until released by a suitably placed pin 35 upon the registering drum. I attain these objects by the mechanism illustrated in the accompanying drawings in which:—

Figure 1 is an elevation view of the detents when the first drum has been removed. 40 Fig. 2 is a plan view of the universal yoke. Fig. 3 is the same as Fig. 1 but with the detents and part of the upright-separation support removed. Fig. 4 is an elevation view of the first and second drums. Fig. 5 45 shows the two straight springs of the compulsion device.

A registering drum 74 (Fig. 1) carrying upon its circular rim numeral figures visible

one at a time through an aperture 51 is the second of a series all freely rotating upon a rod 86.

50

Attached to the drum on one side is either a circle of pins 82 or an ordinary spur wheel. The other side of the drum carries a transfer-pin which may be of any shape but is preferably triangular. The rods 86, 38, 50, 55 32 and 44 run through a series of upright separation-supports 58 and there is one support between each drum and the next one.

The transfer-levers are all alike and there is one for each drum immediately below the 60 circle of pins 82. The transfer-lever 65 is L shaped and is pivoted at 42 upon an arm 43, itself pivoted upon the rod 44. The transfer lever 65 is pointed at 47 and the recess 47^a Fig. 3 is merely to enable it to move 65 without interference from the rod 32 which is necessarily in the position shown. The transfer-lever 65 has attached to it a short rod 64, passing through the aperture 41 Fig. 1 cut in the support 58, to allow the 70 rod 64 to reach the detents 68 and 59 on the nearer side of the support 58.

The spring 45 is attached to the lever 65 and to the support 58 at 46, at such an angle that there is, in addition to the strong pull 75 from left to right, a slight tendency to cause the lever to rise when freed from its detents.

The special key-lever 1 pivoted at 55 has a finger button 2 and a returning spring 3. The universal yoke 10, pivoted at 55 has a 80 rigidly attached crossing rod 13 (Figs. 1 and 2) an antifriction roller 11 and a returning spring 12. The key lever 1 contacts with the yoke 10 at the rod 13 and the yoke 10 contacts with the transfer-lever 65 85 at the roller 11. The key-lever, yoke and transfer-lever are all shown in their highest positions in Fig. 3 and in their lowest positions in Fig. 1.

When the key 1 is depressed, it depresses 90 the yoke 10, which in turn depresses the lever 65. The point 47 descends radially from between two of the pins of the drum and at the same time, the short rod 64 depresses the lever-detent 68, and moves to the 95

right until held by the edge 71 and the spur 63. The key and yoke rise to their normal positions leaving however the transfer-lever depressed and ready to cause transfer whenever the pin 6^a Fig. 4 on the first drum, comes into contact with the point 62 of the lever detent 59 Fig. 1. When this happens the slight displacement of the lever detent 59, first moves the spur 63 to disengage the short rod 64, which releases the lever 65 to the action of the spring 45. When rocked to such position the face 90 of the detent 59 is arranged to form with the edge 71, of the detent 68, a passage for the rod 64, which guides the point 47 of the lever 65 into engagement with the pins 82 of the drum 74.

The lever-detent 68, pulled upward by its spring 70, rises at the same time, the edge 71 still being in contact with the short rod 64, but when the projection 72 of the lever-detent 68, strikes the part 73, the upward movement of the lever-detent 68 is arrested and the short rod 64 frees itself from the edge 71 and moves to the left. The point 47 of the transfer lever 65 also moving to the left, contacts with one of the pins 82 and rotates the drum 74 through one unit.

For confining the movement of the detent 59, the same may be formed with a slot 66 coöperating with a pin 67 projecting from the adjacent partition 58.

In Fig. 3 the transfer lever 65 is shown after it has caused transfer, its point 47 is seen between two of the pins 82, and its movement to the left has been checked by the rod 50. It remains in this position until the next operation of the key 1.

The objects of the lever-detent 68 in addition to holding the short rod 64 in a depressed position are to reduce the force required for a series of transfers from drum to drum and also to cause the transfer-lever 65 to rise slightly before making any movement to the left, in order that this movement may cause the rotation of the drum through one unit.

The pawl 52 with spring 89 is pivoted upon the rod 38 and prevents accidental movement of the drum 74.

The key lever 1 carries a triangular lever 5^a pivoted at 5^b and has a pin 5^c pressed by an upper short spring 5^d and a lower short spring 5^e. These springs maintain the lever 5^a in a position parallel to the key-lever 1, when the point 5^f is in the upper recess 4^a or in the lower recess 4^b, but in the downward movement the point 5^f is raised and in contact with the small-toothed ratchet or milled edge 4^b, part of a large circle whose center is at 55, while in the upward movement the point 5^f is lowered and in contact with the milled edge. The result is a check on the movement unless a complete down stroke and return has been made.

Machines which are key-coupled have a single device for the compulsion of a stroke and devices for the same purpose applied to machines which are not key-coupled maintain the alinement of the lever-pawl with the key-lever by a single spiral spring. The substitution of two straight springs, 5^d and 5^e secures greater precision in this alinement, which is necessary to insure the accurate depression and unfailing detention of all or any of the transfer levers 65.

What I claim is:—

1. In a mechanical adding machine, a device for the transfer from one of a series of registering drums to the next, comprising in combination a lever comprising a substantially vertical arm and a lower arm at substantially right angles to said vertical arm, a frame, a link for said lever and pivoted to said frame at one end, a pivot pin connecting the other end of said link to said vertical arm of the lever, a stop on said frame adapted to arrest the forward movement of the upper end of said lever, a spring tending to press said upper end against said stop and to raise said vertical arm, a pivoted yoke adapted when depressed to engage the horizontal arm of said lever, a spring tending to raise said yoke, and a key lever adapted when depressed to lower said yoke whereby as the lever is lowered by said yoke the upper end of the lever moves at first radially with respect to said registering drum and then rearwardly with respect to the direction of rotation of said drums.

2. In a mechanical adding machine, a device for the transfer from one of a series of registering drums to the next, comprising in combination a compound spring-actuated transfer lever, a spring-actuated pivoted yoke, a key lever adapted to actuate said yoke against the influence of its spring to retract said lever, an abutment projecting laterally from said lever, and of pivoted bar and coöperating spring-actuated detent adapted to embrace said abutment to hold said lever when retracted.

3. In a mechanical adding machine, a device for the transfer from one of a series of registering drums to the next, comprising in combination a compound spring-actuated transfer lever, a spring-actuated pivoted yoke, a key lever adapted to actuate said yoke, against the influence of its spring to retract said lever, an abutment projecting laterally from said lever, a pivoted bar and coöperating spring-actuated detent adapted to embrace said abutment to hold said lever when retracted, an arm on said detent, and an abutment on the preceding drum of said series adapted to engage with said arm to release said detent against the influence of its spring.

4. In a mechanical adding machine, a de-

vice for the transfer from one of a series of registering drums to the next, comprising in combination a compound spring-actuated transfer lever, a spring-actuated pivoted yoke, a key lever adapted to actuate said yoke against the influence of its spring to retract said lever, an abutment projecting laterally from said lever, and a spring actuated pivoted bar and co-operating spring-ac-

tuated detent adapted to embrace said abut- 10
ment to hold said lever when retracted.

In witness whereof I have hereunto set my hand in presence of two witnesses.

CHARLES GILBERT HALL.
